UNITED STATES PATENT OFFICE.

EMILY L. MERRILL, OF BOSTON, MASSACHUSETTS.

ADJUSTABLE GARMENT-RETAINER.

SPECIFICATION forming part of Letters Patent No. 737,435, dated August 25, 1903.

Application filed September 13, 1902, Serial No. 123,270. (No model.)

To all whom it may concern:

Be it known that I, EMILY L. MERRILL, of Boston, in the county of Suffolk and State of Massachusetts, have invented certain new and useful Improvements in Adjustable Garment-Retainers, of which the following is a specification.

This invention relates to the means for lengthening the front of the waist of ladies' garments; and the object of the invention is to provide a simple device of this character which may be adjustably connected with one of the clasp members of corsets, so that the position relatively to the corsets may be varied up or down.

A further object of the invention is to provide a device of this character which will strengthen the corset-clasp at the waist curve thereof. To these ends the invention consists in the improvements which I will now proceed to describe and claim.

Of the accompanying drawings, Figure 1 represents one of my improved garment-retainers in position for use. Fig. 2 represents a detail elevation of a portion of the two members of a corset-clasp with one of my retainers applied to the left-hand member of the clasp. Fig. 3 represents a section on line 3 3 of Fig. 2. Fig. 4 represents a section on line 4 4 of Fig. 2. Fig. 5 represents a perspective view of one of my improved retainers. Fig. 6 is a view similar to Fig. 2, but showing a doubled form of my improved retainer. Fig. 7 represents an enlarged detail on line 7 7 of Fig. 6. Fig. 8 represents a perspective view of the doubled form shown in Fig. 7.

The same reference characters indicate the same parts in all the figures.

The adjustable retainer (shown in Figs. 2 to 5, inclusive) comprises a piece of sheet metal struck up and bent to form a front wall *a*, having a curved edge *a'*, and a rear wall *b*. The said rear wall is slotted to form an integral tongue *c*, which is bent inward toward the front wall, so as to engage the rear of a corset-clasp, as clearly shown in Figs. 3 and 4. The upper edge of the front wall *a* is formed with an extension which is bent outward and downward to form a hook *d*, underneath which the upper edge of skirt-bands or other nether garments may be passed, so that said garments will be held depressed at the front, ac-

cording to the position which the retainer occupies on the corset-clasp *e*. The retainer is readily applied to position by slipping it 55 edgewise onto one of the members *e* of the corset-clasp, as the left-hand one in the drawings, the flattened sleeve of the device comprising the front and rear walls being so shaped as to fit said corset-clasp member. 60 Obviously the retainer may be open along the other edge, however, to permit it to be engaged with the right-hand corset-clasp member. While the sleeve is open, as clearly shown in Figs. 4 and 5, to permit it to be applied 65 to the corset-clasp, it cannot be readily accidentally removed from the corset-clasp member, owing to the curved edge *a'* of the front wall extending around the edge of the clasp member *e*.

It will be readily understood that I may employ more than one of the hook-sleeves shown and described, one above another, as shown by full lines in Fig. 6. When two separate devices are employed, they may be adjusted 75 relatively to each other, so that different garments may be held at different points by means of the hooks *d d*. I may, however, permanently connect two of the devices to a single strip of steel, such a strip being indicated at 80 *f* in Figs. 7 and 8 and being indicated by dotted lines in Fig. 6. When two of the devices are connected together by means of such a strip as here shown, the tongue *c* (shown in Fig. 5) may be dispensed with and an equivalent tongue or tongues formed at *f'* in that portion of the strip *f* located between the two retainers. In Fig. 8 I have represented the devices as connected with the strip *f* by means of rivets extending through the rear wall *b*; 90 but it is to be understood that I do not limit myself thereto, as said strip *f* may be riveted to the front walls *a* of the retainers. When two of the devices are applied, as indicated in Fig. 6, different garments may be connected 95 with the two hooks *d*, this being particularly useful when two garments are to be held and when the two combined would be too thick to be readily held by a single hook. When a device such as shown in Fig. 8 is employed, 100 the steel strip *f* will serve to strengthen the corset clasp or steel *e*, while the resilient character of said strip will permit it to yield for all practical purposes. The retainer herein-

before described is designed for particular use in connection with a shirt-waist and skirt-retainer, such as that which forms the subject-matter of an application for patent filed by me concurrently herewith.

While I have illustrated the device as having but one corset-engaging prong or tongue *c*, it is to be understood that there may be two, three, or four of such prongs.

10 I claim—

1. A garment-retainer comprising a flat sleeve open at one edge to permit it to be applied to a corset-clasp and having a hook extending downwardly from the front wall of the sleeve and having a tongue to bear against the said clasp.

2. A garment-retainer comprising a flat sleeve consisting of a single piece of sheet metal having front and rear walls, said sleeve being open at one edge to permit it to be applied to a corset-clasp, the front wall of the sleeve having a hook extending downwardly from its upper edge, means being provided for holding the device in adjusted position.

3. A garment-retainer comprising a flat 25 sleeve consisting of a single piece of sheet metal having front and rear walls, said sleeve being open at one edge to permit it to be applied to a corset-clasp, the rear wall of the sleeve having an integral inwardly-bent 30 tongue and the front wall of the sleeve having a hook extending downwardly from its upper edge, means being provided for holding the device in adjusted position.

4. A garment-retainer comprising a plurality of flat sleeves permanently secured to a resilient strip of metal, each of the sleeves being open at one edge and having skirt-band-engaging hooks, means being provided for holding the device in adjusted position lengthwise of a corset-clasp.

In testimony whereof I have affixed my signature in presence of two witnesses.

EMILY L. MERRILL.
